194,803

PIPE SUPPORTING BRACKET

Irvin Gant Angel, 1815 Winston St., and William Leroy Hockett, 1203 N. Elam Ave., both of Greensboro, N.C.

Filed Oct. 27, 1961, Ser. No. 67,292

Term of patent 14 years

(Cl. D54—13)

FIG. 1

FIG. 2

FIG. 3

FIGURE 1 is a perspective view of a pipe supporting bracket showing my new design;

FIGURE 2 is a side elevational view of my pipe supporting bracket; and

FIGURE 3 is a top plan view of FIGURE 2.

We claim:

The ornamental design for a pipe supporting bracket, as shown.

References Cited in the file of this patent

Sargent & Co., Catalog No. 100 c. 1953, received in Patent Office Library November 8, 1959, page 302, "S-19040 Clamp."